COMBINED TYPEWRITING AND COMPUTING MACHINE

Henry L. Pitman, Hartford, Conn., assignor to
 Underwood Elliott Fisher Company, New York,
 N. Y., a corporation of Delaware

Application December 30, 1938, Serial No. 248,448

5 Claims. (Cl. 235—60)

This invention relates to typing machines and more particularly to associated mechanism for keeping count of the number of items or the like as they are typed severally on a work sheet.

One use of such mechanism is to ascertain whether all of a certain number or gathering of items have been typed, so that none may be overlooked or omitted.

An object of the invention, therefore, is to provide an efficient, reliably operative item-count recording mechanism suitable for typing machines.

An item counting register is employed and it is a further object to provide means whereby the operation of typing each item, automatically determines the entry of a count therefor in such register. Thus, a count of "1" may be entered in such register automatically with the typing of each item.

The numeral typing agents of the machine may be operated, in correspondence to the item count standing in such register, to copy said count on a record sheet, and it is a further object of the invention that such operation determines clearance of the item counting register so that the latter may finally stand at zero preparatory to counting another number of items.

A further feature of the invention resides in associating with the item-count register a mechanism, operable only when such register has been properly cleared by the total-count typing operation, to print a clear sign to prove that a correct copy of the registered count has been typed.

The invention is herein illustrated as applied to a combined typewriting and computing machine of the kind exemplified in my United States patents, No. 2,090,852 and No. 2,091,717. In such machine, a letter or denomination feeding carriage cooperates with numeral type agents for typing an amount digit by digit and, concomitantly, indexing mechanism cooperates with the numeral type agents and carriage to set up the amount in settable index pins of one or more sets of register bars which are subsequently cycled to run the amount, additively or subtractively, into one or more sets of computing wheels. Suitable carry-over mechanism may be associated, of course, with said computing wheels.

A further object of the invention, with reference to such combined typing and computing machine, is to contrive to employ its kind of computing wheels, indexable register bars and carry over mechanism to constitute an item-count-registering mechanism. To this end the invention provides some further means whereby the typing of each variant item, or some part thereof, auto-

5 matically determines the entry or count of just "1" in such item-count registering mechanism. Any suitable number of these wheels may be provided for item counting. A number of corresponding indexable register bars is provided and these serve mainly for clearing the item counting wheels in that when the total item count is read from said wheels and typed, the total item count is concomitantly set up in said register bars which 10 may then be cycled to subtract the total from and thus clear said wheels.

The foregoing and other objects, features and advantages will be apparent from the following description of the herein illustrated machine and 15 of accounting or itemizing work done thereon.

In the accompanying drawings:

Figure 1 is a side elevation showing mainly 20 register wheel shifting mechanism at the front of the computing base.

Figure 2 is a cross sectional side elevation of the 25 combined typewriting and computing machine embodying the invention.

Figure 3 is a perspective diagram of the item 30 counting register mechanism and its operative connection to carriage operated controls.

Figure 4 is a side view of a register bar, computing wheel, and carry-over train.

Figure 5 is a plan view diagram of the item 35 counting register wheels and register bars.

Figure 5^A is an enlarged scale side elevation of a portion of a rack and cross blades employed in item-count-indexing.

Figure 6 is a diagram showing the operative 40 relation of denominational jacks, a cycling jack and carriage carried tappet-means for engaging said jacks for counting items.

Figure 7 is a perspective illustrating a modification of a connection included in a train from 45 the carriage to a component of the item count registering mechanism.

Figure 8 is an illustration of a work sheet in which entries in a certain column are arranged in a certain way, the items being counted through 50 the typing of said entries.

Figure 9 illustrates a work sheet diagram in which said entries are placed in a different way.

Figure 10 is a diagram illustrating a "0" indexing detail of the item count registering mechanism.

A computing base B is surmounted by a type- 55 writer T.

Key levers 20, Figure 2, having numeral keys 21, and similar key levers 19 having alphabet keys 22 are connected by bell cranks 23 to corresponding

type bars 24 for swinging the latter to a revoluble platen 26. A universal bar 27, escapement dogs 28, escapement wheel 29 and spring motor 30 co-operate, at actuation of the type bars 24, to letter feed a platen carriage 31, the latter having a feed rack 32 engaging a pinion 33 connected to said escapement wheel. The carriage runs on guide rails 34, 35 on the typewriter frame 36.

Denominational tabulating keys 37 may selectively raise denominational stop-reeds 38 into the path of a stop on the carriage and concomitantly the carriage rack 32 is lifted from the escapement pinion 33 by means of a stop-reed-actuated universal bar 39. These and other details of tabulating mechanism may be as shown in the Helmond Patent No. 1,858,447 of May 17, 1932.

The computing base B may have a plurality of sets of computing wheels, each wheel including a pinion 40. Each set of wheels is shiftable downwardly to mesh its pinions 40 with drive racks 42, for addition, or rearwardly to mesh said pinions with drive-rack-driven idlers 43, for subtraction. The drive racks 42 are included in register bars 44 each of which also includes a row of index or digit pins 45.

A single set of denominational jacks 46 operable seriatim by the carriage is operatively connected by connections 41, Figure 2, to a set of master racks 47 corresponding in number to the maximum number of register bars 44 constituting a set of the latter. Said connections 41 are diagrammatically represented at Figure 3. The master racks 47 are connected, by means of rockable cross blades 48, to sets of distributive racks 49 operatively aligned with corresponding sets of register bars 44. Each distributive rack 49 has pivoted thereto a coupler 50 which is movable from the full line normal position to the dotted line position, Figure 2, to connect the distributive rack to the corresponding register bar.

Each set of couplers 50 is movable by means of a shifter plate 51, the several shifter plates being operatively connected to the typing carriage 31. The latter, therefore, traverses a group 52 of cam plates to depress the latter selectively at a computing zone of the carriage travel. A depressed cam plate works through a train, comprising, Figure 2, plate 53, thrust rod 54, linkage 55 and a rock-shaft 56 having a crank wrist connection to the corresponding shifter plate 51, to raise the latter and thereby lift the corresponding set of couplers 50 to operatively connect the corresponding register bars 44 to their distributive racks 49 and thus operatively connect said register bars to the denominational jacks 46.

Thus, when said jacks 46 are depressed seriatim by the carriage at a computing zone, the thereto connected register bars 44 are slightly advanced seriatim to bring their index pins 45 under pin-setting linkages or indexers 58 operable selectively by the numeral key levers 20 through rods 59 depending from the latter. My co-pending application Serial No. 225,762, filed August 19, 1938, now Patent No. 2,202,671, dated May 28, 1940, discloses said cam plate train in fuller detail.

Following the indexing of the carriage selected sets of register bars, a general operator mechanism is cycled to advance and return a general operator cross bar 61 forming a part of said mechanism. In its advance stroke, said cross bar 61 engages the depressed or set indexed pins 45 of the register bars 44 and advances the latter through the medium of pin-engaging levers

62, there being one of these levers, pivoted on the cross-bar 61, for each register bar.

In the initial portion of the general operator cycle, there is an idle period, before any register bar is picked up and advanced by the cross bar 61 and levers 62. During this idle period a rock-shaft 63 of the general operator mechanism may operate computing wheel shifting mechanism 64, represented at Figure 1, to move the computing wheels corresponding to the carriage selected set or sets of register bars into mesh either with the racks 42 or idlers 43.

There is a wheel shifting mechanism 64 for each set of computing wheels and its operation to mesh said wheels with the racks is predetermined by setting a state controller 65, Figure 1, concomitantly with the depression of the corresponding one of the group 52 of cam plates, said corresponding cam plate being one that serves for raising a coupler shifter plate 51.

Said group of cam plates 52 includes a subtraction cam plate 66 deppressible by the carriage concurrently with any one of the register bar set selecting cam plates. Said subtraction cam plate 66 when depressed causes, through mechanism not shown, the state controller 65 to be set to predetermine operation of the wheel shifting mechanism 64 to shift the selected set of computing wheels into mesh with the idlers 43.

At the step of a computing wheel past its carry-over point, it rocks a corresponding lever 68 to lift and thereby release a link 69 from a latch bar 70, Figure 2. Said link 69 is connected to a stationarily fulcrumed lever 71 disposed in operative alignment with the index pin engaging lever 62 for the register bar 44 of next higher denomination. In the absence of a carry-over step of said computing wheel, its corresponding link 69 remains latched on the bar 70 to position said lever 71 so that it has no effect on said next higher denomination pin engaging lever 62 as the latter drives its register bar to the end of its advance. But, when said link 69 is tripped, it is moved endwise by its spring 72 and thus its lever 71 is rocked so that a stud 73, of said lever 71, becomes positioned to react against said pin engaging lever 62 and causes the latter to be rocked, thereby to advance said next higher register bar a carry-over step, as the general operator cross bar 61 nears or completes its advance stroke.

Before the general operator cross bar 61 completes its advance stroke, the latch bar 70 is shifted, by means not shown, from the Figure 4 position leftwardly so as to shift and position the links 69, which are latched over bar 70, with their ends 120 adjacent the normally depressed zero-pins 45, the levers 71 correspondingly being turned counter-clockwise from the Figure 4 position. Normally, the parts have the Figure 4 positions so that the link-ends 120 do not interfere with the slight advance of the register bars to pin-setting positions. These carry-over features so far described are substantially as shown in H. L. Pitman Patent No. 2,078,274, dated April 27, 1937, to which reference may be had for further details.

In its return stroke, the general operator cross bar returns the advanced register bars, but, preceding such register bar return, the computing wheel shifting mechanism 64 is operated to disengage the active computing wheels from their drive racks or idlers.

Figure 8 illustrates a work sheet used for itemizing insurance-policy accounts. Each item

typed on said sheet may include an entry in each of three columns headed, respectively, "Sub No.," "Insurance" and "Premium."

The machine may have two sets of register bars 44 and corresponding sets of idlers 43 and computing wheels 40, these sets being, respectively, for computing the entries typed in the "Insurance" column and the "Premium" column. These sets are diagrammatically represented in Figure 3 by their corresponding sets of distributive racks 49. The carriage has positioned thereon by means of rack structure 74, Figure 2, two column control blocks 75, Figure 2, one for the "Insurance" column and the other for the "Premium" column. Each block presents a tabulating stop 76 for engaging the key selected tabulating stop reeds 38, and a denomination selecting tooth 77 for depressing the jacks 46. Each block may also include a cycling tappet 78 for engaging and depressing a cycling jack 79 which is operative through mechanism, not shown, to cause a power operated cycle of the general operator mechanism, said cycling jack being depressed as the carriage advances after typing the last digit of an entry in the column for which the cycling tappet is set. In the Figure 3 diagram the control blocks are represented by the arrows 75.

Each block 75 also includes a register selecting tappet 80, the one for the "Insurance" column for engaging a cam plate 81, and the one for the "Premium" column for engaging a cam plate 82. Each cam plate is operatively connected by a train, as hereinbefore described, to a corresponding shifter plate 51 indicated diagrammatically at Figure 3. Each cam plate, 81 or 82, is, of course, included in the cam plate group 52, Fig. 2, and when depressed, is kept depressed by its tappet 80 while the carriage traverses a computing zone corresponding to the work sheet column and thus the corresponding shifter plate 51 is kept raised to maintain the corresponding set of couplers 50 in effective position to maintain the corresponding set of register bars 44 operatively connected to their set of distributive racks 49.

The details of structure and operation thus far described are substantially as set forth more fully in the aforesaid patents, No. 2,090,852 and No. 2,091,717, and in my aforesaid application Serial No. 225,762.

There will now be explained the invention relating to counting items such as those listed on the work sheet at Figure 8.

For counting items, the machine may include an item-count registering mechanism comprising, say, three register pinions 40^I and corresponding register bars 44^I having racks 42, Figure 2, idlers 43^I and distributive racks 49^I.

The set of denominational jacks 46 may range from a units-of-cents denomination, the first one at the left, Figure 3, up to a units-of-millions denomination, the last one at the right, Figure 3. In typing dollars and cents amounts a punctuation space step of the carriage is usually effected to separate the tens-of-cents and units-of-dollars places on the work sheet. Therefore, a punctuation space jack 84 is disposed between the tens-of-cents and units-of-dollars jack 46 and when depressed by a selecting tooth 77 depresses a cross bail 85 connected to a locking mechanism, not shown, to lock the numeral key levers 20 at the punctuation space substantially as set forth in my aforesaid application Serial No. 225,762.

The three distributive racks 49^I for the item-count register mechanism are each connected to the corresponding one of the three cross blades 46 that correspond to the first three jacks 46 immediately to the right, Figure 3, of the punctuation space jack 84.

The item count wheels 40^I are rotatably mounted upon an arbor 86 in a frame 87 shiftable to mesh the wheels either with the corresponding racks 42, register bars 44^I, or with the idlers 43^I, said frame having associated therewith one of the wheel shifting mechanisms 64 such as hereinbefore referred to and more fully set forth in the aforesaid Patent No. 2,091,717.

The arbor 86 carries an extra wheel or pinion 40^E disposed immediately to the right of the three item-count wheels 40^I and for said extra wheel 40^E there is an extra register bar 44^E having a row of index pins 45 ranging in value from 0" to "9," and having a rack 42.

An extra distributive rack 49^E having a coupler 50 is associated with said extra register bar 44^E and has spurs or teeth presenting edges 88 for operative connection, as in Fig. 5, with each of the three cross blades 48 corresponding to said three jacks that are immediately to the right of the punctuation space jack 84.

The coupler 50 for the extra distributive rack 49^E has its own individual shifter plate 51^E having an operative connection to a corresponding cam plate 89, said connection being a train such as hereinbefore described and being represented diagrammatically in Figure 3 by the dot-and-dash line 90. A shifter plate 51^I is associated with the three couplers 50 for the three distributive racks 49^I and is operatively connected by a train, as diagrammatically indicated by the dot-and-dash line 91, Figure 3, to a cam plate 92.

The extra pinion 40^E is joined, as by rivets 93, Figure 4, to a circumferentially notched detent disk 94 and to a disk 95. Said disk 95 has carry-over teeth 96 evenly spaced therearound and equaling in number the number of steps (ten in the present instance) which complete a full revolution of said pinion 40^E. One of the carry-over trains, comprising lever 68, link 69 and lever 71, is associated with the extra pinion 40^E and is normally latched over the bar 70 provided for the item-count register. The lever 68 is rocked, as it is passed over by any one of the carry-over teeth 96, associated with said extra pinion 40^E, thereby to release the corresponding link 69, and its lever 71, so that the latter, operatively aligned with the pin engaging lever 62 for the register bar 44^I for the units item count pinion 40^I becomes positioned, in the manner described above, to determine an advance of one step of said units register bar 44^I at a cycle of the general operator mechanism.

Each of the item count pinions 40^I has a numbers dial 97, the several dials being visible through a sight opening 98 in the casing of the computing base. Each of the dials 97 below the one of highest denomination has a single carry-over tooth 99, Figure 5, and a carry-over train 68, 69, 71 such as above described is associated with such tooth for determining a carry-over step of the register bar 44^I of next higher denomination. Obviously, the tooth 99 on the highest dial 97 is usually not used, but is present merely because it is convenient in manufacturing to have the main dials alike.

The entry of a count of "1" in the item count pinions 40^I may be determined by and while typ-

ing a suitable part of the item on the work sheet. In the present illustrative arrangement the typing of an entry in the "Sub-No." column of the Figure 8 work sheet determines the entry of the item count of "1" in said pinions 40^I.

The rack structure 74 on the carriage, therefore carries a column control block, indicated diagrammatically by the arrow 100, Figure 3, for the "Sub-No." column. This control block 100 presents a tabulating stop 76, a denomination selecting tooth 77, a cycling tappet 78 and a tappet 101 for engaging and depressing the cam plate 89 and thereby lifting the shifter plate 51^E to connect only the extra register bar 44^E to the extra distributor rack 49^E.

Any entry in the "Sub-No." column may be a number of from one to three places, for example, "8," or "24," or "323," see Figure 8. Preparatory to typing an entry in the "Sub-No." column, the carriage may be tabulated by means of the appropriate one of the three tabulating keys 37 marked 1, 10 or 100, Figure 3, for starting at the proper place in the "Sub-No." column of the work sheet. Thus, during the course of typing an entry in the "Sub-No." column, the denomination selecting tooth of the column block 100 will depress at least one of the first three denominational jacks 46 immediately to the right of the punctuation jack 84, Figure 3, said three jacks corresponding to the three stop reeds 38 controlled by the aforesaid three tabulating keys 37. Said three jacks are connected by means of their corresponding master racks 47 to the three cross blades 48 that are each operatively connected, see also Fig. 5^A, to the extra distributor rack 49^E by means of the hereinbefore described edges 88 presented by the teeth of said rack 49^E.

Since the "Sub-No." column block 100 also operates, through its tappet 101, to depress the cam plate 89 to raise the shifter plate 51^E to operatively connect said extra distributor rack 49^E by means of its coupler 50 to the extra register bar 44^E, the latter will be slightly advanced to bring its pins 45 under the digit indexers 58 at each depression of one of said three jacks 48 in typing the "Sub-No." entry.

Each register bar may include means whereby when any one of its pins 45 is set, that pin automatically becomes restored by the setting of any other pin, and such means are exemplified in Thieme Patent No. 2,075,557 of March 30, 1937. Briefly described, said means include a pivoted blade 121 on each register bar, Figures 2 and 10, the sides of the pins 45 being notched as at 122, Figure 10, so that a depressed pin is caught and held down by the blade and so that the latter is momentarily turned aside by depressing another pin, the turned aside blade releasing the first depressed pin which becomes restored by its spring 123, Fig. 2. Thus, with the "0" pins normally set in all of the register bars, the setting of a higher pin in any register bar, operates through said means to restore the "0" pin of that bar. Means not shown are also provided and are operative in a cycle of the general operator mechanism, to reset or depress all of those "0" pins that were unset during the indexing thereby to restore all of the higher pins that were set. The zero-pin-resetting means, not shown, may be as illustrated in said Thieme Patent No. 2,075,557 or in Pitman Patent No. 2,258,714, dated October 14, 1941.

Consider now, the typing of the entry "323" in the "Sub-No." column. With the carriage

initially positioned at the hundreds place, the corresponding jack 46 will have been depressed to cause the extra register bar 44^E to be shifted to pin setting position so that the typing of "3" actuates the corresponding indexer 58 to set the "3" pin in said extra register bar 44^E. Similarly at the tens place the typing of "2" sets the "2" pin and the setting of the latter automatically causes the restoration of the previously set "3" pin. At the units place the typing of the "0" must not restore a previously set higher pin. Therefore, the "0" pin 45 in the extra register bar 44^E may be cut off at the top so that it will be out of reach of the stroke of the "0" indexer 58. Said "0" indexer may also be notched as at 103, Figure 10, so as to clear and not affect the "0" pin. The aforesaid zero-pin-resetting means are effective, during cycling, also on the zero pins 45' of bars 44^I and 44^E.

It will be apparent now, that the typing of an entry in the "Sub-No." column will cause some one of the pins from "1" to "9" to be set in the extra register bar 44^E. The typing of a "Sub-No." entry will not effect indexing of the pins 25 of the register bars 44^I because it is designed that the "Sub-No." entry control block 100 has no tappet for working the cam plate 92 and hence said register bars 44^I remain operatively disconnected from the jacks 46 during the typing of 30 the "Sub-No."

Following the typing of the "Sub-No." entry, the carriage may be advanced to the "Insurance" column position. At such advance, the cycling tappet 78 of the sub-column block 100 overrides 35 and depresses the cycling jack 79 and thus causes the general operator mechanism to be cycled. At the beginning of the cycle, the item count pinions 40^I, together with the extra pinion 40^E are shifted into mesh with the racks 42 of their respective register bars. The general operator cross bar 61 in its advance then picks up the extra register bar 44^E and advances it one to nine steps and correspondingly rotates the extra pinion 40^E, the number of steps depending upon 45 whichever pin finally is set in said extra register bar 44^E and engaged by said cross-bar 61.

It will be apparent now, that whatever the extent of rotation of said extra pinion 40^E may be, the number of carry-over teeth 96 associated 50 therewith is sufficient so that the carry-over lever 68 will be rocked at least once and therefore invariably the link 69 will be tripped to determine a carry-over step of the units register bar 44^I, for entering a count of "1" in the units item wheel 55 40^I. At each tenth entry of a count of "1" in said units item pinion 40^I, the carry-over tooth of the latter, of course, operates its carry-over train to determine a carry-over step of the next higher register bar 44^I and pinion 40^I, and the latter in 60 due turn similarly operates by means of its carry-over train to carry to the next higher pinion 40^I.

It will be perceived in Figure 8, that the "Sub-No." entries may be typed so that their "units" or "last" places are vertically aligned. Figure 9 shows a work sheet wherein each "Sub-No." entry always begins, irrespective of its number of figures, at the same vertical line in the "Sub-No." column, as is indicated by the vertical alignment 65 of all the initial figures of the entries. This figure 9 method of "Sub-No." entry placement makes it unnecessary to operate the tabulating mechanism preparatory to typing the various "Sub-Nos." and thus the first figure of each "Sub-No." entry may be typed immediately upon returning the carriage to an item line start position,

which may be gauged by the usual line start margin stop for the carriage, not shown.

When using the Figure 9 placement of the "Sub-No." entries, the "Sub-No." column unit 100 is placed so that when the carriage is fully returned or positioned to start the typing of an entry, the denomination selecting tooth 77 depresses the first denominational jack 46 immediately to the right of the punctuation jack 84 as in Figure 6. Since, with such Figure 9 placement of the "Sub-No." entries, the typing of a significant figure invariably occurs when said first jack is depressed, said first jack need be the only one connected to the extra register bar 44^E and hence the extra distributive rack 49^E need be connected only to the cross blade 48 corresponding to said first jack as is represented in Figure 7 by the single connection 102.

The total item-count may be read at any time from the dials 97 of the item count pinions 40^I and copied at a suitable place on the work sheet. Such total item count may be typed immediately to the right of the entries in the "Sub-No." column and within said column as exemplified at 103', Figures 8 and 9. In copying the total item count, the appropriate numeral type key levers 20 are, of course, operated and concomitantly, the total may be set up in the pins 45 in the item count register bars 44^I. The carriage 31 is, therefore, provided with a total count control block represented diagrammatically by arrow 104, Figure 3. This control block 104 includes a denomination selecting tooth 77, and also includes a tappet 105 for engaging the cam plate 92 associated with the coupler shifter plate 51^I. Said control block 104 may also include a cycling tappet 78 and a tabulating stop 76. By means of said tabulating stop 76 and the appropriate tabulating key 37, the carriage is positioned for typing the first figure of the number-of-items total as read from the item count dials. When so positioned, the denomination selecting tooth 77 has depressed the corresponding denominational jack 46 and the tappet 105 has, of course, depressed the cam plate 92 to connect the register bars 44^I to jacks 46. During the typing of the items-total, the extra register bar 44^E obviously is not connected to said jacks because it is designed that the item-total-column unit 104 has no tappet for the cam plate 89. Said column unit 104 may also have a tappet 106 for operating the subtraction cam plate 66 to determine automatically that the total as set up in the pins 45 of the register bars 44^I will be run subtractively through the idlers into the item count pinions 40^I when the machine is cycled and thus said pinions 40^I will be cleared if the total has been correctly copied. Since the extra register bar 44^E need not function subtractively, it will be obvious that no idler 43 need be provided and should be omitted for said extra register bar 44^E. It will be obvious that, should one of the three cross blades 48 corresponding to the counter register bars 44^I be carriage-operated to move the corresponding distributive rack 49^I for item-count-total-indexing, the extra rack 49^E will be moved merely idly, but should not operate any other cross blade 48. It will also be obvious that this may be provided for by narrowing the teeth, presenting the edges 88, to afford clearances 88^a, Figure 5A, so that while a carriage-operated cross blade 48 may move rack 49^E idly, the idle movement of rack 49^E will not in turn move another blade 48. Springs 115, see also Fig. 2, may be applied as needed to some of the racks connected to the cross blades 48 so that the springs urge the

racks and cross blades to normal positions in which the upper back corners of the blades may bear against fixed stop teeth, not shown herein, but exemplified in the aforesaid Patent No. 2,090,852.

5 A clear sign star 114, Figures 8, 9, may be printed alongside of the total, by means of mechanism which can be operated only if the total has been correctly copied, that is, if all of the item pinion dials 97 stand at "0." Inasmuch as the purpose of the item count mechanism is to record a true count of all the items typed so that it may be ascertained that no item has been overlooked, it will be evident that the clear sign printing to indicate the accuracy of the count, as read and typed, is important.

The clear sign printing mechanism may be of the kind shown in the Hoyt Patent No. 1,256,309 of February 12, 1918. Briefly described, said mechanism includes, for each pinion 40^I a scalloped detent disk 107 fastened to said pinion, and a spring pressed detent 108' engaging said disk. The detents 108' enter deeper into the notches of said disks 107 when the pinions 40^I stand at "0" than when said pinions stand at any other position. Thus, when all the pinions 40^I stand at "0," the detents 108' universally permit a detent pressing universal bar 109 to stand clear of a star key 110 so that the latter may be depressed. The depression of the star key 110 operates to release a normally latched spring pressed train 111 to cause said train to operate a lever 112 of a star printing type action which is included in the typewriter and includes a bell crank and star printing type bar like 23, 24. A cycle of the general operator mechanism may follow the printing of the star and said train and type action are restored during the cycle. The universal bar 109 may be independent of the spring pressed detent 108' engaging the detent disk 94 for the extra pinion 40^E and for this purpose, said detent 108' associated with the extra pinion 40^E may have a wide slot 113, Figure 3, to clear said universal bar 109.

45 The punctuation jack 84 and the two jacks 46 at the left thereof may have the forward parts of their top end portions cut away as at 116, Figures 3 and 6, so that they will not be depressed by the teeth 77 of the column blocks 100, 104 or by the tooth 77 of the column block 75 for the "Insurance" column. These three teeth 77 are narrowed and placed longitudinally of their respective blocks so as to engage only the forward half portions of the tops of the other jacks 46. The tooth 77 in the block 75 for the "Premium" column need not, in consideration of the usually 50 comparatively limited magnitude of a premium entry, engage the two jacks 46 at the right of the group and therefore these two jacks are cut away as at 117, Figures 3 and 6, at the rear halves of their top ends and the "Premium" column tooth 77 is narrowed and placed longitudinally of its block so as to engage only the rear half portions of the remaining jacks which include the punctuation jack 84 and the two dollars-and-cents jacks immediately to the left of said jack 84. These dollars-and-cents jacks are usually used in the "Premium" column.

55 The tabulating stop reeds 38 are mounted to slide vertically in a fixture 118. The group 52 of cam plates and the cooperative lower plates 53 are mounted to slide vertically in a fixture 119. Said fixtures 118 and 119 are suitably supported by the frame 36 of the typewriter.

60 The extra register bar 44^E may have associated

therewith a link 69' and its lever 71' presenting a stud 73' for controlling the general operator cross bar lever 62 associated with said extra register bar 44E. Said link 69' is permanently latched over the bar 70 and is never released therefrom and is provided with an index pin engaging stop, such as 120, Figure 2, for preventing overthrow of the extra register bar 44E.

Variations may be resorted to within the scope of the invention, and portions of the improvements may be used without others.

What is claimed is:

1. In an accounting machine, the combination of selectively operable character agents and a step-by-step feeding carriage cooperative therewith, a plurality of jacks operable seriatim by said carriage when an entry is made, a single rack indexable by means of said agents, under control of said jacks, to determine a movement of the rack which varies according to the agent operated, said rack having operative connection to each of said jacks whereby carriage operation of any jack renders the rack indexable by any of said character agents, an entry counter, and means responsive to each rack movement irrespective of its variance to enter a uniform count in said counter.

2. In an accounting machine; the combination of selectively operable digit indexers, a step-by-step feedable carriage cooperative with said indexers, a register comprising a plurality of orders of computing wheels, an indexable driver for each wheel, jacks corresponding in number and order to the drivers, an operative connection, including a switchable coupler, between each jack and its driver, means operable under control of the carriage to switch the couplers jointly to position to connect said jacks to their corresponding drivers, said jacks being operable seriatim by the carriage to move the drivers to position for indexing by said indexers, an extra indexable element movable to position for indexing by said indexers, said element being subsequently operable to a variant extent corresponding to the indexing, means responsive to the variant extent of operation of said element to enter a uniform count in said wheels, an operative connection, including a switchable coupler, between said element and all of said jacks, and means operable under control of said carriage to switch said last-named coupler to position to connect said element to all of said jacks to render said element movable to indexing position by means of the carriage and any one of the jacks.

3. In a machine of the character described, in combination, numeral keys, a step-by-step feedable carriage cooperative therewith, a plurality of computing wheels of different denominations, a drive rack for each wheel, each drive rack having settable index pins, indexers corresponding to an operable by means of said keys, an element having settable index pins, a set of jacks, one for each drive rack, operable seriatim by said carriage, connections, including two devices selectively operable by the carriage, one device being operable to connect said drive racks individually to corresponding ones of said jacks, the other device being operable to connect said element to all of said jacks jointly, to enable the carriage to move said racks and element to index-receiving position relatively to said indexers, cycling mechanism for said racks and element, and means responsive to the cycling of said element to make a uniform entry in said computing wheels irrespective of the value indexed in said element.
4. In a machine of the character described, in combination, selectively operable numeral-value indexers, a member, means advancing said member a step at each operation of an indexer in respect to an amount of more than one order, said member being advanceable in an amount zone and being positionable outside of such zone, a computing wheel, an actuator indexable for different extents of subsequent operation, means enabling the member to place the actuator in index-receiving relation to said indexers for each denomination in the amount zone, said actuator and indexers being out of said relation when the member is positioned outside of such zone, and means for translating the subsequent operation of the actuator into uniform entry in said wheel irrespective of the indexed extent of actuator operation.
5. In a machine of the character described, in combination, a computing wheel, an actuator indexable for different extents of subsequent operation, a set of numeral-value agents operable one at a time for each order of an amount of more than one order, means cooperative with said agents for indexing the actuator at each operation of an agent for each order of the amount, and means for translating the subsequent operation of the actuator into uniform entry in said computing wheel irrespective of the indexed extent of actuator operation.
